UNITED STATES PATENT OFFICE

GEORGE HENRY WALKER, OF WORCESTER, ENGLAND, ASSIGNOR TO HEENAN & FROUDE LIMITED, OF WORCESTER, ENGLAND

HYDRAULIC HEAT-GENERATING SYSTEM

Application filed May 26, 1928, Serial No. 280,918, and in Great Britain June 23, 1927.

This invention relates to improvements in hydraulic absorption apparatus for the generation of heat.

In the destruction of power by means of a hydraulic absorption apparatus, heat is generated and is imparted to the circulating water or other liquid with which the apparatus is supplied and it has been proposed to store the resulting hot water or steam in a closed vessel, known as a heat accumulator, from which it can be withdrawn for use as required. It has also been proposed to connect the hydraulic apparatus or heat generator by means of piping or other passages to the heat accumulator so that a circulation of water between the two units of the apparatus may be permitted.

A difficulty connected with the practical application of such schemes lies in the method of regulating the consumption of power to suit that which is available at the shaft of the apparatus. Conditions may arise in which the amount of power consumed by the hydraulic apparatus if allowed to develop full resistance to rotation would be in excess of the power supplied so that the speed of the shaft would fall, to the detriment of the efficiency of other parts of the system.

The object of the present invention is to provide a simple and efficient method of regulating the power consumption which will meet the above mentioned conditions.

In hydraulic apparatus such as hydraulic brakes or dynamometers there usually exists a vortex or vortices at the centre of which exists a low pressure and at the outer diameter a high pressure and in the prior U. S. specification No. 1,035,700 to Harrison means are described for admitting to the centre of the vortices air under atmospheric pressure, which means consisted of holes or pipes communicating between the external atmosphere and the parts of the hydraulic brake corresponding with the centre of rotation of the vortices.

According to the present invention the steam space existing in a heat accumulator is connected with the interior of the hydraulic heat generator at a point or points at or

near the centre of the vortex or vortices where, under running conditions, the pressure is relatively low.

Such connection to the point or points at or near the centre of the vortex or vortices may be made by passages formed in the vanes of the power absorbing elements in a manner similar to that described in the prior U. S. specification No. 1,035,700 and these passages are connected by a steam pipe with the steam space in the heat accumulator instead of being connected to the external atmosphere. The water inlets and outlets of the hydraulic apparatus are both coupled up through a suitable valve or valves with the water space of the heat accumulator so that water can be drawn away by a circulating pump or by a natural fall from one portion of the accumulator, and after passing through the hydraulic heat generator can be discharged again into the accumulator.

The invention will be described with reference to the accompanying drawings:—

Fig. 1 is a diagrammatic view of the heat generator, heat accumulator and other accessories.

Fig. 2 is a horizontal section through the hydraulic heat generator.

Fig. 3 is an enlarged section on line 3—3 Fig. 2 showing the passages through the vanes of the power absorbing element connecting the steam pipe to the centres of the vortices.

Fig. 4 is a detail sectional view of distributing valve controlling the flow of water to and from the heat generator and the heat accumulator, the valve being set for minimum load.

Fig. 5 is a detail sectional view of the distributing valve, the valve being set for maximum load.

Fig. 6 is a diagrammatic view of hydraulic heat generator showing an alternative arrangement of valve control.

The hydraulic heat generator A is similar to that described in specification No. 1,035,700 with a rotor B mounted on the shaft B¹ driven from a suitable prime mover and a stator C. Passage c are formed in the vanes of the stator C connecting the points corre-

sponding to the centres of the vortices with the annular spaces c^1 and these annular spaces c^1 are connected by the steam pipe D with the steam space e at the top of the heat 5 accumulator E. An isolating or regulating valve d may be arranged in the steam pipe D whereby the flow of steam from the heat generator A to the heat accumulator E or vice versa may be shut off or adjusted.

Passages c^2 are also formed in the vanes of the stator C connecting the water spaces between the vanes with the annular space c^3 and this annular space c^3 is connected to the water inlet passages F^1 arranged one at either 10 side of the generator and terminating in a single passage or conduit F. The water outlet conduit G is connected to the annular space B^2 surrounding the rotor B. The water inlet conduit F and the water outlet conduit G are connected to the water space e^1 of the heat accumulator E through a distributing valve H controlled by an actuating rod K from a suitable governor (not shown in the drawings) so that the flow of water into and 15 out of the generator is regulated and the power consumed in the heat generator is adjusted. Thus for example, when the inlet valve is wide open admitting water freely to the heat generator, and the outlet valve is almost closed, the power absorbing elements 20 are packed full of water and the power consumed is the maximum.

On the other hand, when the inlet valve is closed and the outlet valve wide open, the 25 water has a free passage from the heat generator, which by virtue of its rotation and the centrifugal force imparted to the water, can empty itself or nearly so, and in these circumstances the power consumed is a minimum. 30 Intermediate positions of the valves result in intermediate powers being absorbed.

A circulating pump J which may be of the motor-driven centrifugal pattern is preferably employed in the circulating system so 35 that the pressure of water supplied to the inlet F of the heat generator A may be raised in excess of that due to the difference in head between water level in the heat accumulator E and that in the heat generator A. By 40 means of suitably arranging the valves or the ports of the distributing valve, the pump suction instead of drawing water from the accumulator may, upon occasion, be put into communication with the outlet G of the heat 45 generator and the pump discharge may be connected to the accumulator E, thus enabling the pump to extract water from the heat generator and so nearly or entirely draining it and reducing the power consumed to almost 50 nil.

A suitable balanced distributing valve for controlling the flow of water is shown in Figs. 4 and 5, the setting shown in Fig. 4 being for the minimum load and the setting shown in Fig. 5 being for the maximum load. The

valve is formed with six ports, the port h^1 connected to the water inlet F of the heat generator, the port h^2 connected to the water space e^1 of the heat accumulator E, the port h^3 connected to the suction side of the circulating pump J, the port h^4 connected to the bottom of the water space of the heat accumulator E, the port h^5 connected to the water outlet G from the heat generator A and the port h^6 connected to the discharge side of the pump J. The actuating rod K is formed with several pistons k^1 , k^2 , k^3 and k^4 .

When the valve is set for the minimum load as in Fig. 4 the port h^4 is cut off from the port h^3 by the piston k^3 and consequently the feed from the accumulator is choked, the port h^5 connected to the water outlet G from the heat generator A is in communication with the port h^3 connected to the suction side of the pump J and the port h^6 connected to the discharge side of the pump J is in communication with the port h^2 connected to the water space e^1 of the heat accumulator E so that the pump J is drawing water from the water outlet G of the heat generator A and delivering it to the heat accumulator E. The port h^1 connected to the inlet F of the heat generator A is choked by the piston k^1 so that water is not passing into the generator.

When the valve is set for the maximum load the actuating rod K has moved into the position shown in Fig. 5 so that the port h^4 connected to the water space e^1 of the heat accumulator is in communication with the port h^3 connected to the suction side of the pump J, the port h^5 connected to the outlet G of the heat generator H is closed by the piston k^3 , the port h^2 connected to the heat accumulator E is choked by the two pistons k^2 and k^3 and the port h^6 connected to the discharge side of the pump A is in communication with the port h^1 connected to the water inlet F of the heat generator A. The pump J is thus drawing water from the accumulator E and discharging it to the water inlet F of the heat generator whilst the water outlet G from the heat generator is choked.

The actuating rod K on which the pistons k^1 , k^2 , k^3 and k^4 are mounted is connected through link gear or any other convenient manner to the governor which may be of the centrifugal or other pattern, arranged so that any tendency of the heat generator and prime mover to increase their speed, automatically increases the power consumed by the heat generator, while any tendency for the speed to fall has a contrary effect.

Suitable isolating valves may be arranged in the conduits. Thus the valves f, g are arranged between the heat generator A and the distributing valve H, the valves j, j^1 between the valve H and the pump J, the valves e^2 , e^3 between the valve H and the heat accumulator E, the valve d in the steam pipe D.

Instead of a distributing valve H as de-

scribed above the water inlet F and the water outlet G of the heat generator A may be each provided with a separate valve F², G² as shown in Fig. 6. These valves F² and G² as shown, are of the butterfly type, but any other suitable balanced type may be employed. They are connected together by link gear M or in any other convenient manner so that as one valve opens the other closes. The link gear M is connected to an actuating rod K connected to the governor (which is not shown in the drawing).

The steam pipe D may be enclosed within a pipe of larger diameter which outer pipe may be employed to convey the heated liquid from the casing of the heat generator A to the accumulator E. This avoids condensation of steam which, under certain conditions, may interfere with the effective operation of the heat generator. Alternatively the steam pipe may be efficiently lagged with heat insulating material for the same purpose.

What I claim as my invention and desire to protect by Letters Patent is:—

1. In an hydraulic heat generating system comprising an hydraulic heat generator, a heat accumulator and conduits connecting the generator to the accumulator, a rotor and a stator forming the heat generator, water spaces in the rotor and in the stator in which spaces vortices are set up during rotation of the rotor, a pipe connecting the centres of the vortices with the steam space in the heat accumulator, conduits connecting the water inlet and water outlet of the generator to the water space in the accumulator, a multi-ported distributing valve connected in said conduits, a plurality of pistons by which the ports are controlled and an operating rod upon which the pistons are mounted.

2. In an hydraulic heat generating system comprising an hydraulic heat generator, a heat accumulator and conduits connecting the generator to the accumulator, a rotor and a stator forming the heat generator, water spaces in the rotor and in the stator in which spaces vortices are set up during rotation of the rotor, a pipe connecting the centre of the vortices with the steam space in the heat accumulator conduits connecting the water inlet and water outlet of the generator to the water space in the accumulator, a multi-ported distributing valve connected in said conduits, a circulating pump connected to the distributing valve, a plurality of pistons by which the ports are controlled and an operating rod upon which the pistons are mounted.

3. In an hydraulic heat generating system comprising an hydraulic heat generator, a heat accumulator and conduits connecting the generator to the accumulator, a rotor and a stator forming the heat generator, water spaces in the rotor and in the stator in which spaces vortices are set up during rotation of

the rotor, a pipe connecting the centres of the vortices with the steam space in the heat accumulator, conduits connecting the water inlet and water outlet of the generator to the water space in the accumulator, a multi-ported distributing valve connected in said conduits, a circulating pump connected to the distributing valve, a plurality of pistons by which the ports are controlled, an operating rod upon which the pistons are mounted and isolating valves in the conduits.

In testimony whereof I have hereunto set my hand.

GEORGE HENRY WALKER.
